UNITED STATES PATENT OFFICE.

ROBERT REX DOWNIE, OF BEAVER FALLS, PENNSYLVANIA, ASSIGNOR TO KEYSTONE DRILLER COMPANY, OF BEAVER FALLS, PENNSYLVANIA, A CORPORATION OF PENNSYLVANIA.

EXCAVATING MACHINE.

Application filed January 8, 1925. Serial No. 1,978.

To all whom it may concern:

Be it known that I, ROBERT REX DOWNIE, a citizen of the United States, residing at Beaver Falls, in the county of Beaver and State of Pennsylvania, have invented a new and useful Excavating Machine, of which the following is a specification.

This invention relates to excavating machines, and particularly to those of the drag stick, ditcher type, such as that disclosed in U. S. Patent No. 1,511,114, granted to me October 7, 1924, and it consists primarily in an improved device for controlling the position of the ditcher scoop.

15 The object of the present invention is to provide an improved construction, which will permit a much greater latitude in the positioning or spotting of the loaded scoop when elevated as for dumping, and to permit greater positiveness and accuracy in controlling the position of the scoop within that range than is otherwise feasible.

To the attainment of the foregoing, the invention comprises means for temporarily modifying the action of the system of pivoted parts about the outer end of the boom during the dumping phase of the cycle of operation. More specifically, it consists in the provision of means for suspending the action of the connecting bar pivot, so that the connecting bar and the ditcher stick remain relatively motionless during such interval as the boom remains above a predetermined angle of elevation. In the specific embodiment of the invention, which is herein described and illustrated, this means consists in the provision of suitable stops on the connecting bars and ditcher stick adapted to contact with each other when these parts have reached their predetermined angle of relative approach.

40 The specific construction of the invention, as well as its advantages and its mode of operation, will be more fully explained in the detailed description which follows, which is to be read in connection with the accompanying drawings illustrating the invention in its preferred form.

In the accompanying drawings:

50 Figure 1 is a side elevation of a machine embodying the invention and showing the boom raised.

Figure 2 is a similar view on an enlarged

scale, showing the boom in horizontal position.

55 Figure 2^a is a side elevation of the ditcher stick and scoop, and the portion of the boom to the right of the line a—b in Figure 2.

Figure 3 is an enlarged detail view showing the relative arrangement of the invention in connection with the boom, ditcher stick and connection bar.

60 Figure 4 is a plan view of the connecting bar and ditcher stick.

Figure 5 is a detail view of the stop member secured to the connecting bar.

65 Figure 6 is a detail view of the connection between the ditcher stick and connecting bar.

70 Figure 7 is a detail view of the connection between the ditcher stick and the boom.

The invention is shown in connection with an excavating machine 1, having a mast 2, which is connected thereto by a pair of vertically aligned pivots 3. The boom 4 is pivotally connected at 5 to the mast, and is adapted to be swung upwardly and downwardly. The outer end of the boom has extension irons 6 secured thereto, the outer ends of which are traversed by a pivot bolt 7 for supporting the ditcher stick 8. The ditcher stick is formed from a pair of channel bars, as shown in Figures 3, 4, 6 and 7, and secured to the rear face of the stick is a bearing 9, provided with a cap 10 for receiving a sleeve 11 in which the pivot bolt 7 is secured. The sleeve 11 extends beyond the bearings sufficiently, so that the head and nut of the bolt 7 may be secured thereto without binding the extension irons 6 of the boom.

75 At the upper end of the ditcher stick 8, on the side opposite to the pivot bolt 7 and somewhat above the same, a bearing 12 is secured, and receives a sleeve 13 in which a pivot bolt 14 is secured. A connecting bar 15 is pivoted at one end on the sleeve 13, and comprises a pair of spaced strap irons, intermediately connected by a bracket 16, and traversed at their rear ends by a pin 17 on which a hoisting sheave 18 is mounted. A scoop 19 is carried at the lower end of the ditcher stick 8, and has a hauling bail 20, which is connected by a hauling cable 21 to a suitable source of power on the machine. 80 A second cable 22 passes over the hoisting

sheave 18. The operation of raising and lowering the boom 4, and the ditcher stick 8 carried thereby, and of swinging the ditcher stick and the scoop 19 outwardly 5 and inwardly for filling and for positioning preparatory to dumping the same is controlled entirely through the cables 21 and 22, as explained in the above mentioned patent. It has been found, however, that when the pivot bolts 7 and 14 are 10 properly located with respect to the line of tension through the connecting bar 15 to give the best results with the greatest conservation of power, under certain conditions, 15 the pivot bolt 7 will be substantially in the line of pull between the cable 22 and the connecting bar pivot 14, so that it is difficult to swing the scoop 19 outwardly to gain the desired spotting range. In order to prevent 20 this condition, without altering the relative locations of the pivot bolts 7 and 14, I have formed the bracket 16 with depending stop arms 23, which are adapted to engage co-operating stop arms 24, which are formed 25 on the bearing cap 10 and extend upwardly and rearwardly therefrom, thus providing means for positively and effectively swinging the scoop outwardly by paying out the cable 21, and drawing in on the cable 22 30 when the pivot bolt 17 is in what may be termed a dead center position.

Without the provision of the cooperating stop arms or abutments 23 and 24, a scoop has only a very limited spotting range when 35 elevated to the height ordinarily required for dumping, and is not positively or accurately controlled within such range as it does have. The immediate reason for this shortness of range is lack of sufficient outward thrusting force to swing the loaded 40 scoop outwardly beyond its plumb position, or to swing it quickly and positively even out to a plumb position. This lack of force is, in turn, due to the fact that at this elevation of the boom, the pivot 7 closely approaches, and at extreme elevations, actually 45 intersects the line of tension between the pivot 14 and the point toward which the cable 22 is drawn. This will be made clear 50 by regarding the bolt 7 about which the ditcher stick swings, as a crank center, the line between the bolt 7 and the bolt 14 as a crank arm, and the bolt 7 to which the power is applied as the crank end. Now, when the 55 bolt 7 or the crank center approaches or intersects the true line of tension extending from the machine to the bolt 14, the crank is nearly or actually on dead center position, and the force exerted upon it by the hoisting 60 line is in the general direction of the length of the crank, and not in a direction advantageous for causing rotation.

The depending part of the stick 8, with the loaded scoop at its lower end, tends, of course, to hang plumb; that is, in such a

position that the center of gravity of the stick and scoop combined is directly underneath the pivot 7; and with the proportional arrangement of the parts most advantageous in actual excavation, the stick is of such a 70 length and the scoop is of such a weight that they hang practically in their plumb position, and are only negligibly affected by the slight tendency of the upper arm to rotate. 75

Referring now to the present improvement, the effect of using the abutments 23 and 24 for limiting the angular approach of the connecting bar 15 toward the ditcher stick 8 is to render the upper crank arm, 80 above described, temporarily inoperative, and to substitute therefor another crank arm of a much more effective length and angle, which may be represented by a line from the pivot 7 to the hoisting sheave pin 17 and 85 which effectively serves to alter the normal position of the stick, throughout such interval as the members 23 and 24 are in abutting relation.

The effect of the abutments 23 and 24, 90 therefore, is to cause the loaded and elevated scoop to hang outwardly when in equilibrium at a desirable distance from the boom, and to seek that remote position quickly when the hauling line 21 is paid out. Spotting is effected by paying out or taking in sufficiently to bring the scoop to the exact position desired for dumping. In 95 actual practice, the construction herein described has been found not only to give the 100 desired degree of positiveness of action, but to increase the spotting range to about twice the range possible without this improvement, and without any offsetting disadvantages. 105

It is believed that the attainment of this increased spotting range by other means, such as by altering the relative location of the pivots 7 and 14 with respect to each other and to the ditcher stick, is not feasible 110 in this type of machine; it will be either prohibitively wasteful of power, or would sacrifice to a prohibitive degree the outward reach of the stick when lowered and extended at the beginning of the digging operation. The position of the pivots 7 and 115 14 is actually governed by considerations of power, economy, and necessary digging travel or sweep of the scoop and can not, therefore, be altered in order to gain the 120 desired spotting range or outward dumping reach. 125

In excavators of this type, for example, the pivot 14 is located a certain distance above the pivot 7. The purpose of this relative arrangement is to cause the tension of the hoisting line 22 not only to support the stick and attached parts, but also to maintain a pull upon the upper end of the stick 130 in the direction of the machine, and, with the 135

boom acting as a stiff link, to cause the stick to swing outwardly nearly into longitudinal alinement with the boom. It is obvious that this initial reach is desired, and, in fact, indispensable when starting an excavation down through a level surface. The stick assumes and remains in this position of rest or equilibrium, except as restrained or retracted from it by the hauling line 21, which is attached to the bail 20 on the scoop. Digging is effected by first lowering the boom, stick and scoop in this extended position until the teeth of the scoop engage the material to be excavated, and then winding in the hauling line.

It will be seen that the hauling line and the hoisting line are in some degree actually antagonistic; that is, the hauling line, in order to draw the scoop toward the machine, must first offset, by a portion of its own power, whatever outward thrust the hoisting line may be exerting upon the scoop through the stick as a lever. This antagonism, though objectionable in itself because it reduces the net live power available for actual digging, is in practice tolerable because it permits operating with cables only, and permits three distinct positive movements of the scoop, namely, inward, outward and upward, with but two cables. Also, it will be seen that the measure of this antagonism lies in the relative proportions of two spacings, the distance from the stick pivot 7 to the pivot 14, as compared to the distance from the pivot 7 to the pivot of the bail 20.

Now, in order that the least possible amount of power may be neutralized in the digging operation, by reason of the antagonism of the opposed pulls on the cables 21 and 22, the point 14 of the hoisting line attachment is located at the shortest possible distance above the fulcrum or pivot 7 of the ditcher stick; that is, the shortest possible distance which will constitute a leverage of sufficient length to cause the stick when in equilibrium to be in the outward position which is necessary for starting the excavation; and the point of attachment of the hoisting line is located in such a direction from the pivot 7, and with such angular relation to the length of the stick as to give the greatest possible effect to the power applied to the cable 22 for swinging the lower end of the stick outwardly preparatory to digging. The necessities of efficient use of power and sufficient digging range govern the location of the pivot 14 with reference to the pivot 7, both as to distance and direction, so that it can not be altered in order to secure the advantage of increased spotting or dumping range, but the latter is secured in a practical manner by the provision of the abutting members 23 and 24.

While I have shown and described specifi-

cally one form in which the invention may be embodied, it is apparent that the same may be modified to some extent without departing materially from the essential features of the invention. It is my intention, therefore, to include all such modifications within the scope of the appended claims.

What is claimed is:

1. In an excavating machine, the combination of a boom mounted to move upwardly and downwardly, a member pivotally connected to the outer end of the boom, a scoop carried by said member, a hoisting line, means connecting the hoisting line to the scoop carrying member at a point above the pivotal connection of the latter to the boom, and means automatically preventing relative motion of said connecting means and the scoop carrying member during a certain part of the operating cycle.

2. In an excavating machine, the combination of a boom mounted to move upwardly and downwardly, a ditcher stick intermediately pivoted to the outer end of the boom, a hoisting line, means pivoted to the stick above its pivot for connecting the hoisting line therewith, and means dependent upon the operation of the boom for temporarily suspending the action of the pivot at the upper end of the stick during a certain part of the cycle of operation.

3. In an excavating machine, the combination of a boom mounted to move upwardly and downwardly, a ditcher stick intermediately pivoted to the outer end of the boom, a connecting member pivoted to the stick above the pivotal connection of the latter with the boom, a hoist line attached to the connecting member, and means for limiting the angular approach of the stick to said connecting member.

4. In an excavating machine, the combination of a boom pivoted to move upwardly and downwardly, a ditcher stick intermediately pivoted to the outer end of the boom, a link member pivotally connected to the upper end of the stick, a hoisting line connected to said link member, and means for temporarily fixing said link member at a predetermined angle with relation to the stick during a certain part of the cycle of operation.

5. In an excavating machine, the combination of a boom pivotally mounted to move upwardly and downwardly, a ditcher stick intermediately pivoted to the outer end of the boom, a link member pivotally connected at one end to the upper end of the stick, a hoisting line connected to the other end of the link member and extending inwardly therefrom, said link member being normally free to move about its pivot and to normally remain in a position of alinement with the direction of tension in the hoisting line, and means for causing the inward movement of

the lower end of the stick to be opposed, during a part of the operating cycle, by the tendency of said link member to remain in alinement with the direction of tension in 5 the hoisting line.

6. In an excavating machine, the combination of a boom pivoted to move upwardly and downwardly, a ditcher stick pivotally supported at the outer end of the boom, a 10 scoop secured to the lower end of said stick, a connecting bar pivoted to the stick above the pivotal connection between the latter and the boom, a hoisting line connected to said bar, and inter-engageable abutments on 15 the connecting bar and ditcher stick respectively, limiting their relative approach toward each other.

7. In an excavating machine, the combination of a boom pivoted to move upwardly and downwardly, a ditcher stick pivotally supported intermediate its ends by the outer end of the boom, a scoop secured to the lower end of said stick, a connecting bar pivoted to the upper end of the stick, a 20 hoisting line connected to said bar, a hauling line connected to the scoop, an abutment secured to and extending downwardly from the connecting bar, and an abutment secured in rigid relation to said stick and extending 25 inwardly and upwardly therefrom toward the bar and engageable by the first mentioned abutment to limit the relative angular approach of the connecting bar toward the ditcher stick.

8. In an excavating machine, the combination of a boom pivoted to move upwardly and downwardly, a ditcher stick pivotally connected intermediate its ends to the outer end of the boom, a scoop secured to the 30 lower end of said stick, a hoisting line connected to said stick, a hauling line connected to the scoop, and an abutment secured to the under side of the connecting bar and en-

gageable with a part carried by the boom to oppose downward movement of said connecting bar about its pivot. 45

9. In an excavating machine, the combination of a boom pivotally mounted to move upwardly and downwardly, a ditcher stick intermediately pivoted to the outer end of the boom, a link member pivotally connected at one end to the upper end of the stick, a hoisting line connected to the other end of the link member and extending inwardly therefrom, said link member being normally 50 free to move about its pivot and to remain in a position of alinement with the direction of tension in the hoisting line, and means for deflecting the link member out of alinement with the direction of tension of the hoisting 55 line whenever the boom and stick and direction of tension of the hoisting line come into such a relationship that, except for said deflecting means, the direction of tension of the hoisting line would pass approximately 60 through the pivotal connection between the boom and the stick.

10. In an excavating machine, the combination of a boom mounted to move upwardly and downwardly, a ditcher stick 70 pivotally connected to the outer end of the boom, a scoop carried by said ditcher stick, a hoisting line, means connecting the hoisting line to the ditcher stick at a point above the pivotal connection of the latter to the 75 boom, and means for deflecting upwardly the direction of the pull exerted by the hoisting line upon the ditcher stick whenever the line of pull would otherwise pass approximately through the pivotal connection between the boom and the stick. 80

In testimony, that I claim the foregoing as my own, I have hereto affixed my signature.

ROBERT REX DOWNIE.
